UNITED STATES PATENT OFFICE.

E. M. MIX AND J. E. MIX, OF WESTFIELD, NEW YORK.

IMPROVEMENT IN PADLOCKS.

Specification forming part of Letters Patent No. 58,278, dated September 25, 1866; antedated September 15, 1866.

To all whom it may concern:

Be it known that we, E. M. MIX and J. E. MIX, of Westfield, in the county of Chautauqua and State of New York, (formerly of Ithaca, N. Y.,) have invented certain new and useful Improvements in Padlocks; and we do hereby declare that the following is a full and exact description thereof, reference being had to the accompanying drawings, making part of this specification, in which—

Figure 1 is a front view, with the drop or escutcheon removed. Fig. 2 is an internal view, the front plate being removed. Fig. 3 is an edge view of the lock, with the escutcheon raised at right angles thereto. Fig. 4 is a front elevation of the escutcheon as closed.

Like letters of reference indicate corresponding parts in all the figures.

Our invention relates to the class known as seal-locks; and it consists in the pivoting and arrangement of the seal-plate or cover so as to swing or slide on a plane with the face of the lock; in fastening the same, by means of a pin on one of the tumblers, so that it cannot be released without moving the tumbler by a key or other instrument, thereby injuring the seal; also in the construction and arrangement of the hinge of the escutcheon and the spring by which it is kept closed; and, further, in the combination and arrangement of the sliding seal-plate with the hinged escutcheon for covering and protecting the former.

As represented in the drawings, A, Fig. 1, is the front plate of the padlock; B, the shackle; C, one of a series of tumblers; and D, the dog, which engages with the notch *a* of the shackle (when inserted, it being self-locking); *b* is the guide-post for the key, and *e* is the key-hole, and *f* a recess surrounding it, to receive the seal.

G is the seal-plate, provided with a key-hole, corresponding with *e*, which is hung on the pivot *h*, so as to be swung aside to enable the seal to be placed in the recess *f*, when it is replaced.

When the shackle is unlocked the plate *G* is free to swing on its pivot, but having been locked, and the seal inserted, and the plate is returned to its proper position, it strikes the pin *i* on the tumbler *C*, and moves the same

until it falls into the notch *j* of the plate, and is there held, so that the seal cannot be uncovered unless the tumbler is moved by the turning of the key to unlock the lock, or the insertion of some other instrument through the key-hole, which cannot be done without breaking the seal.

The key-hole and seal-plate are covered by the drop or escutcheon *K*, which is hinged to the lock in a manner that keeps it closed when not forcibly raised. This is effected by means of a bow-shaped spring, *l*, which lies recessed on the under side of the escutcheon, to which it is attached at its center, the two ends being provided with holes, through which the hinge-pin *m* passes, making the spring form a part of the hinge itself.

The side or ear pieces *o o* of the plate *N*, to which the drop *K* is attached, are beveled toward each other, their faces forming a continuation of the diverging ends of the spring. The effect of these beveled ears is to compress the two ends of the spring closer together when the escutcheon is raised at right angles, so that the force of the spring is exerted to return it and hold it down to the face of the lock.

The spring is concealed within the escutcheon, and the latter may be made, if desired, of sufficient size to conceal the seal-plate *G*, so that its presence would not be suspected by persons unacquainted with the construction.

The arrangement of the key-plate, moving on a plane with the face of the lock, and the escutcheon hinged to disclose the key-hole only by being raised, has many advantages. The escutcheon may be made strong enough to protect the seal-plate from injury by receiving a blow or falling on a hard substance, while it can be made with a joint sufficiently tight to exclude water and dirt from entering the key-hole or destroying the seal.

What we claim as our invention, and desire to secure by Letters Patent, is—

1. Securing the seal-plate *G* in position over the seal-recess by means of the pin *i* on the tumbler *C*, so that when locked it cannot be released without moving the tumbler, substantially as set forth.

2. In combination with the hinged escut-

eon K, the spring l, pin m, and beveled ear-pieces o o, whereby the spring is made to constitute a self-closing hinge for the escutcheon, arranged and operating substantially as shown and described.

3. The arrangement of the seal-plate G, in relation to the face A of the lock, and the escutcheon K, whereby the plate moves on a plane between the two, in the manner and for the purposes set forth.

4. The combination and arrangement of the vertically-rising escutcheon K, with the recess

f, and swinging seal-plate G, whereby the former is made to conceal and protect the latter, substantially as shown.

In witness whereof we have hereunto signed our names in the presence of two subscribing witnesses.
